UNITED STATES PATENT OFFICE.

GEORGE B. GRANT, OF LINDEN, MASSACHUSETTS.

WATER-MOTOR.

SPECIFICATION forming part of Letters Patent No. 241,800, dated May 24, 1881.

Application filed February 3, 1881. (No model.)

To all whom it may concern:

Be it known that I, GEO. B. GRANT, a citizen of the United States, residing at Linden, in the county of Middlesex and State of Massachusetts, have invented a new and useful Improvement in Water-Motors, of which the following is a specification.

My improvement relates to water motors or engines by which the force of a stream of water under pressure is caused to give motion to machinery; and it relates to an improved means of governing such a motor, or regulating the supply of water according to the work it has to do.

15 The drawing shows the mechanism in full.

The motor M is any form of rotary engine, water-wheel, or hydraulic engine, and with its construction or mode of operation this invention is not concerned. It is any device which 20 admits or discharges water through a pipe, I, and causes it to give rotation to a drive shaft, d.

On the drive-shaft d is an arm, a, which carries a pawl, p, acting on a ratchet-wheel, v, fixed to a driven shaft, S, so that that shaft is 25 driven by the shaft d, but may keep up its motion by its own momentum when the shaft d is stopped.

Any form of friction-clutch may take the place of the pawl and ratchet.

30 Upon the shaft S, or turning with it, is a gov-

ernor, G, of any form, which operates, through a lever, L, or any equivalent device, to open and close the governor-valve V on the pipe I.

The operation of the motor is as follows: The force of the water gives rotation to the 35 shaft d, and through the ratchet-connection to the shaft S. When the speed of the shaft S reaches any assigned limit the governor G shuts the valve V and stops or retards the motor. The ratchet-connection p and v allow 40 the shaft S to revolve freely until the work it is doing exhausts the power stored up in the fly-wheel F, and causes the decrease of speed through the governor to open the valve V and start the motor again. 45

I am aware that a pawl-and-ratchet connection has been used between a water-motor and the machinery it drives, and also that a governor has been applied to check the supply of water to a water-motor; but 50

What I claim as my invention, and desire to secure by Letters Patent, is the following:

In combination, the motor M, driving-shaft d, pawl and ratchet p and v, driven shaft S, governor G, and governor-valve V, substantially as described. 55

GEO. B. GRANT.
